CUT, A CORPORATION OF DELAWARE.

STOP MECHANISM FOR TALKING MACHINES.

Application filed June 6, 1918. Serial No. 238,550.

To all whom it may concern:

Be it known that I, JOHN E. RENHOLDT, a citizen of the United States of America, and a resident of Bridgeport, Connecticut, 5 have invented a new and useful Improvement in Stop Mechanism for Talking Machines, which invention is fully set forth in the following specification.

This invention relates to stop mechanism, 10 and particularly to stop mechanism especially designed for use in talking machines.

In machines of the latter type, a sound-box operatively connected to a sound-conveying member, which together will be referred to as a traveling element, has relative movement to a rotary record-support, which support, or any other suitable rotary member in the drive of said support from the motor of the machine, will be hereinafter 20 referred to as a rotating element, the sound-box and sound-conveying member generally being fed across the record-support by the coaction of the former with the groove in the sound-record tablet. It is an object of this 25 invention to provide stop mechanism of improved construction which will stop the rotation of the record-support or other rotating element upon the completion of the traverse of the sound-box and sound-conveying 30 member.

A further object of this invention is to provide stop mechanism of the character referred to with improved means whereby a predetermined number of revolutions of 35 the rotating element must occur before said stop mechanism can come into action, whether the traveling element be stationary or not.

A still further object of the invention is 40 to provide a stop mechanism of the type characterized with means for throwing the same out of operation at will to the end that the machine may be controlled solely by the operation of manual means.

Yet another object of the invention is to 45 provide a stop mechanism of the type in question wherein one of the two members respectively moved by the traveling and rotating elements is moved into coacting relation with the other of said members by movement of one of said elements.

Other objects relate to the provision of a stop mechanism of the type referred to which is simple in construction, inexpensive

to manufacture and install, and efficient in 55 operation.

Stated broadly, the invention comprises, in combination with a rotating element and a traveling element, stop mechanism, means for automatically actuating said stop mechanism upon the stopping of the traveling element, and means for rendering said automatic means inoperative at will. In the preferred construction, said stop-actuating mechanism comprises coacting members, 60 shown as under the control of the traveling and rotating elements respectively, and means, shown as driven by the traveling element, for moving one of said members into coacting relation with the other of said members. Means are also preferably provided 65 whereby said members assume a coacting relationship only after a predetermined number of revolutions of the rotating element, such means being shown as comprising 70 a member intermittently advanced by timing mechanism into operative position to move one of said first-named members into coacting relation with the other of said members. Said stop-actuating mechanism, 75 in the form shown, comprises a member moved by the traveling element, a member oscillated by the rotating element, an intermediate member oscillated by the second member and adapted to coact with the first 80 member to effect the actuation of the stop mechanism, and means to position said intermediate member so that the oscillations of said second member will move said first member. 85

The invention is capable of receiving a variety of mechanical expressions one of which is shown on the accompanying drawings, but it is to be expressly understood that the drawings are for purposes of illustration only and are not to be construed as a definition of the limits of the invention, reference being had to the appended claims 90 for that purpose.

In said drawings, wherein the same reference characters are used to designate corresponding parts in the several figures,—

Fig. 1 is a top plan view of a talking machine embodying the present invention, parts being broken away to show parts positioned 95 therewith;

Fig. 2 is a side elevation;

Fig. 3 is a bottom plan view;

Fig. 4 is a sectional elevation on an enlarged scale;

Fig. 5 is a perspective view of the elements of the stop mechanism;

5 Fig. 6 is a transverse section on the line 6—6 of Fig. 4;

Fig. 7 is a perspective view of the neutralizing pawl;

10 Fig. 8 is a perspective view of the cam member;

Fig. 9 is a transverse section on an enlarged scale, on the line 9—9 of Fig. 1; and

Fig. 10 is a detail view of the brake element.

15 Referring in detail to said drawings, 1 designates a motor of any suitable construction. While in the embodiment illustrated on the drawings the motor is shown as a spring motor, it is to be expressly understood that the invention is of equal utility when applied to a machine driven by an electric motor. The motor 1, through suitable gearing, drives the spindle 2 of the usual rotary record-support 3 which carries the 20 record-tablet 4. Mounted for coaction with the record-groove of said tablet 4 is the usual or any suitable sound-box 5 carrying a suitable stylus 6, said sound-box being supported on a sound-conveying member or 25 tone-arm 7 of any suitable construction. In the form shown, said tone-arm 7 is bent laterally at 8 and journaled for vertical movement on an elbow 9 which is rotatably supported in a collar 10 of a tone-arm support 11, here shown as integrally connected with the motor-board 12.

In the form illustrated, the shank 13 of 30 said elbow 9 extends within the collar 10 below the plane of the motor-board 12 and has suitably connected thereto adjacent its lower end a cam member 14 comprising a collar 15 for embracing said shank 13 and a cam portion 16 connected to said collar 15. Cam portion 16 is provided with a face 17 35 concentric with the axis of rotation of the tone-arm elbow 9 and an inclined face 18 for a purpose that will hereinafter appear. The portion of collar 10 protruding below the plane of the motor-board 12 is suitably 40 cut away, as shown at 19, to permit of movement of the cam member 14 with the tone-arm 7 through a suitable arc.

Tone-arm support 11, in the form shown, 45 is hollowed out at its underside at 20, and rectilinearly movable within the recess thus provided is a slide 21 suitably supported from the tone-arm support, as by headed screws 22 received through elongated slots 23 in the slide 21. Pivotally supported from 50 the slide 21 is a lever member 24, said slide being provided with a depending boss 25 on which said lever member is pivotally received and retained by a screw 26. Said boss also carries between the member 24 and 55 the head of the screw 26 a cam bushing 27

in position to engage and cooperate with the cam faces on member 14. To maintain cam bushing 27 in cooperative relation with said cam faces, a spring 28, attached at one end to a lug 29 on the slide 21 and at its 70 opposite end to a lug 30 projecting downwardly from the tone-arm support 11, normally urges said slide and the member 24 in the direction of cam member 14. Member 24 at its outer end is provided with a 75 transverse head portion 31 shaped to provide two or more projections 32 and 33 respectively. In the form shown, said projections are provided by cutting notches in the edge of said head portion 31.

80 Suitably mounted on the turn-table spindle 2 is a knurled collar 34, the same being shown as retained in position by the setscrew 35. Mounted for cooperation with said knurled collar 34 is a knurled eccentric 36, the same being supported in any suitable way, as by a screw 37, from an oscillating member 38. While, in the form shown, the collar 34 and eccentric 36 have been provided with knurled surfaces, it is to be expressly understood that such is not essential, as any other suitable friction surfaces could be employed instead, or said collar and eccentric might be provided with gear teeth. Member 38 is mounted for rectilinear oscillation in any suitable way, as by supporting the same between bosses 39 on the motor-frame 40 and headed screws 41 extended through elongated slots 42 in said oscillating member. To normally maintain eccentric 95 36 in cooperative relation with said collar 34, the oscillating member 38 is normally urged toward said collar by a spring 43 attached at one end to said oscillating member 38 and at its opposite end to a pin 44 100 projecting upwardly from the motor-frame. Pivotally mounted on the outer end of oscillating member 38 is an arm 45, the same being shown as pivoted to the member 38 by a screw 46 between the head of which and said arm is a spring washer 47 for preventing too free movement of said arm. Arm 45 at its outer end is provided with an upstanding lug 48 designed for engagement with the projections 32 and 33 as will 105 be explained hereinafter.

110 Pivoted at 49 to the side of the oscillating member 38 is a pawl 50 provided with a tooth 51. Mounted for rotation on the motor-frame 40 is a ratchet gear 52 the teeth of which are in the path of oscillation of tooth 51 on pawl 50 as the latter is carried backward and forward with the oscillating member 38. Gear 52 is a mutilated gear to provide a blank space at 53 for a purpose to 115 be hereinafter explained. Said gear is mounted for rotation in any suitable way, as by a screw 54, and between the head of said screw and said gear is shown a coiled spring 55 to prevent too free rotation of said 120 125 130

gear. Gear 52 also carries an upstanding member 56 designed to engage and position the lug 48 on arm 45 for coaction with the projections 32 and 33 on member 24.

5 Also pivoted on the motor-frame at 57 is a stop-actuating member 58 provided at its outer end with an upstanding lug 59 in the path of movement of head 31 on member 24. Member 58 also carries adjacent its 10 outer end a pawl 60 pivoted to said member at 61 and provided at one end with an arm 62 which is normally held in engagement with lug 59 by a spring 63. At its opposite end said pawl 60 is provided with a tooth 15 64 adapted to engage a tooth of the mutilated gear 52 and rotate said gear.

Any suitable stop mechanism may be operated by said stop-actuating member 58. In the form shown, a brake device 65 is carried 20 by an arm 66 depending from the member 58 in position to engage the usual friction disk 67 of the governor mechanism. It is to be expressly understood, however, that said brake device by suitable variation may 25 be made to engage and brake any other suitable rotating element or, if the motor be electric, be made to operate a suitable switch mechanism. In the structure illustrated, said brake device comprises a brake pad 68 30 supported in a carrier 69 which may have a limited rectilinear movement in a shell 70 suitably mounted in said arm 66. A spring 71 in said shell 70 between the head of the carrier 69 and a screw 72 normally urges the 35 brake pad to its outermost position and cushions the shock of engagement thereof with the element braked.

Any suitable device for moving the stop mechanism into and out of starting position 40 may be employed. In the form shown, a bell-crank lever 73 is pivoted at 74 to the motor-frame and has at one end an up-standing lug 75 designed to engage in a slot 76 provided in the end of stop-actuating member 58. The opposite end of said lever 45 73 extends, as shown at 77, to a position outside the periphery of the motor-board where it may be conveniently operated. Means are also provided for retaining the starting lever 50 73 and stop-actuating member 58 in the starting position and for moving said members to stopping position after initial actuation of the same. Such means may take the form of a toggle spring connected to and 55 movable across the point of engagement of members 73 and 58, or, as illustrated on the drawings, lever 73 may be provided with a ridge 78 for frictional engagement with a plate 79, a spring 80, attached at one end to 60 said plate and at its opposite end to a suitably mounted screw 81, urging said members 73 and 58 to stopping position as soon as the end of ridge 78 passes out of engagement with plate 79.

65 It is frequently desirable to render the

automatic stop-actuating member inoperative so that the machine may be stopped solely by manual operation of the stop-actuating members. To this end a neutralizing pawl 82 is pivotally mounted, as by a screw 70 83, on the motor-board 12, said neutralizing pawl being shown as provided with a hub 84 for receiving the lower end of said screw. Said pawl is provided with a pair of stop lugs 85 and 86 and an upstanding finger 87 75 88 which may be moved into the path of oscillation of pivoted arm 45. To retain the pawl in the position to which it is adjusted, a spring 88 is received between the hub 84 and the motor-board under sufficient tension 80 to retain said pawl in whichever position it may be placed. Screw 83 is shown provided with a knurled operating head 89 to facilitate the adjustment of the pawl, and a stop 90 suitably connected to the motor-board depends into the path of the lugs 85 and 86.

Operation: Assume first that the neutralizing pawl is in the position shown in full lines in Fig. 1 wherein the upstanding finger 90 87 is out of the path of oscillation of the arm 45. The machine is started by moving the projecting end 77 of lever 73 from its extreme left-hand position to its extreme right-hand position as shown in Fig. 1. During 95 this movement, lug 75 on lever 73, by engagement with the wall of the slot 76 in member 58, causes the latter to move in a clockwise direction about its pivot 57 whereby the arm 66 withdraws brake device 65 100 from engagement with the governor disk 67. This movement of lever 73 also brings ridge 78 into engagement with plate 79, moving the latter against the tension of spring 80, and the frictional contact of said ridge 105 and plate is sufficient to retain the lever 73 and stop-actuating member 58 in the starting position. Motor 1 now begins to rotate the spindle 2 and record-support 3.

Cam member 14 is mounted on the shank 110 13 of tone-arm elbow 9 so that the inclined face 18 is in engagement with cam bushing 27 when the tone-arm and sound-box are to one side of the record-support 3 and also, preferably, when the sound-box is at the beginning of the record-groove, say of the usual ten-inch record-tablet. Reproduction is started by moving the stylus 6 of the sound-box 5 into engagement with the groove of the record-tablet 4. During the 115 initial advance of the tone-arm, cam member 14, which rotates with the tone-arm elbow 9, moves its inclined face 18 out of engagement and its concentric face 17 into engagement with the cam bushing 27. During 120 the movement of inclined face 18 over the cam bushing 27, the slide 21 is moved outwardly against the tension of the spring 28 until the head 31 of member 24 is in position to coact, at the proper time, with the pivoted 125 130

arm 45 and to engage, when the traveling element ceases its traverse, the upstanding lug 59 of actuating member 58. Thereafter, the arcuate face 17 of cam member 14 rides 5 over the cam bushing 27 without changing the position of the slide 21.

When the motor starts rotation of the spindle 2, the knurled collar 34, by cooperation with the knurled eccentric 36, oscillates the member 38. Assuming that the ratio of members 36 and 34 is two to one, member 38 will be advanced to the left in Fig. 1, at each second revolution of the record-support. At each advance of the member 38, pawl 50 engages its tooth 51 with one of the teeth of the ratchet gear 52, advancing the latter through the space of one tooth. Assuming, for purposes of illustration only, that there are fourteen teeth on 20 the ratchet gear 52, it will therefore take twenty-eight revolutions of the turn-table spindle 2 before a full rotation of the ratchet gear 52 is completed. During the period that said gear is making its rotation, arm 25 45 is free to rotate on its pivot 46 and, even if at the beginning of the oscillations of the member 38 the lug 48 on said arm 45 should contact head 31, said arm will simply be moved freely on its pivot 46 in an anti- 30 clockwise direction. When gear 52 has made a complete rotation, however, the upstanding member 56 is brought into the path of movement of arm 45 and said arm is thereafter maintained in position for co- 35 action with the projections 32 and 33 on head 31, as the mutilation 53 on the gear 52 is now in the path of oscillation of tooth 51 on pawl 50 and 52 is no longer advanced intermittently by said pawl.

Member 24 is in effect a lever pivoted on the boss 25. At the initial movement of the tone-arm into cooperative relation with the record-support, the clockwise rotation of cam member 14 by engagement with the 45 bushing 27 causes the lever member 24 to move on its pivot 25 in an anti-clockwise direction to the limit defined by any suitable stop such, for example, as the wall of the slot in the tone-arm support 11 through 50 which said member projects. After member 56 has been advanced through its complete rotation and into the position shown in Figs. 1 and 5, arm 45 is maintained by said member in such a position that movement of member 38 to the left in Fig. 1 causes the upstanding lug 48 on arm 45 to engage the projection 32 on head 31 and move member 24 in a clockwise direction into approximate stop-actuating position with its head 31 just 55 out of engagement with the upstanding lug 59 on member 58. During the period when member 38 is moving to the right in Fig. 1, the clockwise movement of the tone-arm 7 and the cam member 14 causes member 24 60 to return in the opposite or anti-clockwise

direction, until lug 48 on arm 45, positioned by member 56, again engages projection 32 during the next forward movement of member 38 and moves said member 24 in a clockwise direction. 70

As long as the tone-arm continues its traverse, lever member 24 is thus moved backward and forward through a slight arc owing to the alternate and intermittent action of the cam member 14 and arm 45 on 75 its opposite ends, it being understood that while the arm 45 is moving said member 24 in a clockwise direction the cam bushing 27 slides freely over the face 17 of cam member 14. When, however, the tone-arm ceases 80 its traverse, lever member 24 is no longer subjected to a force tending to move the same in an anti-clockwise direction. Therefore, following its movement into approximate stop-actuating position by engagement 85 therewith of arm 45, it retains such position and, upon the next advance of arm 45, the upstanding lug 48 engages the second projection 33 on head 31 and said head is thereby moved into final stop-actuating position, engaging and moving the upstanding lug 59 on member 58. 90

Movement of lever member 58 by engagement of head 31 with upstanding lug 59 causes lever 73, through the cooperation of lug 75 and slot 76, to move in a clockwise direction until the end of ridge 78 passes out of engagement with plate 79, whereupon the spring 80 quickly throws members 73 and 58 into stopping position, wherein 100 brake pad 68 engages governor disk 67 and stops the machine, the shock of the engagement being absorbed by the spring 71. During this movement of member 58, pawl 105 60 engages its tooth 64 with one of the teeth on gear 52, rotating the latter gear so as to withdraw space 53 from the path of tooth 51 and advancing a tooth on said gear into position for engagement by tooth 51 when the machine is next started. 110

In case it be desired to throw the automatic stop mechanism out of operation so that the machine can be stopped solely by manual actuation of lever 73, the neutralizing pawl 82, which has stood with its lug 86 in engagement with stop 90, is moved by rotation of knurled head 89 until lug 85 engages said stop 90, in which position the upstanding finger 87 on said pawl is advanced into the path of movement of the lug 48 on arm 45. If, now, the machine is started, said finger 87 will receive the thrust of the arm 45 just before lug 48 can engage a projection on the head 31, even after the member 56 has completed its rotation and is 120 in the position shown in Fig. 5. Member 24, therefore, can receive no impulse to move the same into engagement with lug 59 on member 58, and the motor will continue to run until lever 73 is moved in a 125 130

clockwise direction to move stop-actuating member 58 to the position wherein brake device 65 will engage the governor disk 67.

While the embodiment of this invention 5 illustrated on the drawings has been described with considerable particularity, it is to be expressly understood that the invention is not to be restricted to the form shown, as the same is capable of receiving a 10 variety of mechanical expressions, some of which will readily suggest themselves to those skilled in the art, while certain parts thereof are capable of use without other parts thereof. Reference is therefore to be 15 had to the claims hereto appended for a definition of the limits of the invention.

What is claimed is:—

1. In combination with a rotating element and a traveling element, means for 20 automatically stopping said rotating element upon the stopping of the traveling element, and means for rendering said first-named means inoperative at will.

2. In combination with a rotating element 25 and a traveling element, stop mechanism, means for automatically actuating said stop mechanism upon the stopping of the traveling element, and means for throwing said automatic means out of operation.

30 3. In combination with a rotating element and a traveling element, stop mechanism, means for automatically actuating said stop mechanism upon the stopping of the traveling element, means for manually actuating said stop mechanism, and means for rendering said automatic means inoperative at will whereby said stop mechanism may be actuated only by said manual means.

40 4. In combination with a rotating element and a traveling element, stop mechanism, means moved from the rotating and traveling elements respectively and coacting to 45 actuate said stop mechanism upon the stopping of the traveling element, and means to prevent the coaction of the means moved by the rotating elements and the means moved by the traveling element.

50 5. In combination with a rotating element and a traveling element, stop mechanism, a member moved by the traveling element, a driven member coacting therewith to actuate said stop mechanism upon the stopping of the traveling element, and means to prevent the coaction of the member moved by the 55 traveling element and the driven member.

60 6. In combination with a rotating element and a traveling element, stop mechanism, a member moved by the traveling element, a driven member adapted to engage the same and cooperate therewith to actuate said stop mechanism upon the stopping of the traveling element, and a member movable into the path of said driven member to prevent the engagement thereof with said first member.

7. In combination with a rotating element 65 and a traveling element, stop mechanism, a movable member controlled by the traveling element and normally in an inoperative position, means driven by the traveling element for moving said member into operative position, and a driven member coacting with said first member in said last-named position to actuate said stop-mechanism upon the stopping of the traveling element. 70

8. In combination with a rotating element 75 and a traveling element, stop mechanism, a member driven by the rotating element, a member adapted to coact therewith to actuate said stop mechanism upon the stopping of the traveling element, and means operated by the traveling element for moving said second member into coacting relation with said first member. 80

9. In combination with a rotating element and a traveling element, stop mechanism, 85 members moved by said elements respectively and adapted to coact to actuate said stop mechanism upon the stopping of the traveling element, and means driven by one of said elements for moving one of said 90 members into coacting relation with the other of said members.

10. In combination with a rotating element and a traveling element, stop mechanism, members moved by said elements respectively and adapted to coact to actuate said stop mechanism upon the stopping of the traveling element, a spring normally maintaining one of said members out of coacting relation with the other of said 100 members, and a cam driven by one of said elements for moving said last-named member into coacting relation with the other said member. 95

11. In combination with a rotating record-support, a motor and a tone-arm, stop mechanism, members moved by said motor and tone-arm respectively and adapted to coact to actuate said stop mechanism upon the stopping of said tone-arm, and means 105 moved by the tone-arm as it advances over said record-support for moving one of said members into coacting relation with the other of said members. 110

12. In combination with a rotating record-support, a motor and a tone-arm, stop mechanism, a member driven by the motor, a member moved by the tone-arm and adapted to coact with said first member to actuate said stop mechanism upon the stopping 115 of the tone-arm, a spring normally maintaining said second member out of coacting relation with said first member, and a cam driven by the tone-arm for moving said second member into coacting relation with said 120 first member. 125

13. In combination with a rotating element and a traveling element, stop mecha-

nism, a member moved by the traveling element, a member moved by the rotating element and adapted to coact with said first member to actuate said stop mechanism upon 5 the stopping of the traveling element, said second member being normally out of coacting relation with said first member, and means becoming operative after a predetermined number of revolutions of said rotating 10 element to move said second member into coacting relation with said first member.

14. In combination with a rotating element and a traveling element, stop mechanism, a member moved by the traveling element, a member moved by the rotating element and adapted to coact with said first member to actuate said stop mechanism upon the stopping of the traveling element, said second member being normally out of coacting 15 relation with said first member, means to move said second member into coacting relation with said first member, a gear for advancing said last-named means into operative position, and a pawl driven by the 20 rotating element for rotating said gear.

15. In combination with a rotating element and a traveling element, stop mechanism, a member moved by the traveling element, a member adapted to coact with said first member to actuate said stop mechanism upon the stopping of the traveling element, means driven by the rotating element for oscillating said second member, and other 30 means driven by the rotating element for moving said second member into coacting relation with said first member after a predetermined number of revolutions of the rotating element.

16. In combination with a rotating element and a traveling element, stop mechanism, a member moved by the traveling element, a member adapted to coact with said first member to actuate said stop mechanism upon the stopping of the traveling element, 40 means driven by the rotating element for oscillating said second member, means for moving said second member into coacting relation with said first member, a gear for advancing said last-named means into operative 45 position, and a pawl driven by the rotating element for rotating said gear.

17. In combination with a rotating element and a traveling element, stop mechanism, a member moved by the traveling element, a member adapted to coact with said first member to actuate said stop mechanism upon the stopping of the traveling element, means driven by the rotating element for oscillating said second member, means for 55 moving said second member into coacting relation with said first member, a pawl and mutilated gear for advancing said last-named means into operative position, said pawl thereafter moving idly in the mutilation of 60 said gear, and means operated by the actu- 65

ation of said stop mechanism for advancing the teeth on said gear into operative relation with said pawl.

18. In combination with a rotating element and a traveling element, stop mechanism, 70 a member moved by the traveling element, a member adapted to coact with said first member to actuate said stop mechanism upon the stopping of the traveling element, operative connections with the rotating element for oscillating said second member, a member for moving said second member into coacting relation with said first member, and means driven by the rotating element for intermittently advancing said last-named 75 member into operative position.

19. In combination with a rotating element and a traveling element, stop mechanism, a member moved by the traveling element, a member adapted to coact with said first member to actuate said stop mechanism upon the stopping of the traveling element, operative connections with the rotating element for oscillating said second member, a member for moving said second member into 80 coacting relation with said first member, and timing mechanism for advancing said last-named member into operative position.

20. In combination with a rotating element and a traveling element, stop mechanism, 90 a member actuated by the rotating element and carrying a pivoted arm, a member moved in one direction by the traveling element, and means for positioning said arm so that the impulses of said first member will move said second member in the opposite direction, said members coacting to actuate said stop mechanism upon the stopping of the traveling element.

21. In combination with a rotating element and a traveling element, stop mechanism, a lever moved in one direction by the traveling element, a member actuated rectilinearly by the rotating element and carrying 100 a pivoted arm, and means for positioning said arm so that the impulses of said member will move said lever in the opposite direction, said member and lever coacting to actuate said stop mechanism upon the stopping of the traveling element.

22. In combination with a rotating element and a traveling element, stop mechanism, a lever having projections and moved in one direction by said traveling element, a member actuated by the rotating element 110 and carrying a pivoted arm, and means for positioning said arm to engage one of the projections on said lever and move said lever in the opposite direction, said arm upon the stopping of the traveling element engaging 120 a second of said projections on said lever to move said lever to stop-actuating position.

23. In combination with a rotating element and a traveling element, stop mechanism, a stop-actuating member, a member 125

- 5 moved in one direction by the traveling element, a member actuated by the rotating element and carrying a pivoted arm, and means for positioning said arm so that the impulses of said last-named member will move said second member in the opposite direction and, upon the stopping of the traveling element, into engagement with the stop-actuating member.
- 10 24. In combination with a rotating element and a traveling element, stop mechanism, a stop-actuating member, a member moved in one direction by the traveling element, a member oscillated by the rotating element and adapted to engage said second member to move the same in the opposite direction, said last-named member upon the stopping of the traveling element moving said second member into engagement with
- 15 20 said stop-actuating member, and means to position said third member so that the same will engage and move said second member.
- 25 25. In combination with a rotating element and a traveling element, stop mechanism, a stop-actuating member, a member moved in one direction by the traveling element, a member oscillated by the rotating element and adapted to engage said second member to move the same in the opposite direction, said last-named member upon the stopping of the traveling element moving said second member into engagement with
- 30 35 said stop-actuating member, and means to position said third member so that the same will engage and move said second member, said positioning means moving into operative position only after a predetermined number of revolutions of said rotating element.
- 40 26. In combination with a rotating element and a traveling element, stop mechanism, a member moved by the traveling element, a member actuated by the rotating element, an intermediate member oscillated by said second member and adapted to coact with said first member to actuate said stop mechanism upon the stopping of the traveling element, and means to position said
- 45 50 intermediate member so that the impulses of said second member will move said first member.
27. In combination with a rotating element and a traveling element, stop mechanism, a member moved by the traveling element, a member actuated by the rotating element, an intermediate member oscillated by said second member and adapted to coact with said first member to actuate said stop mechanism upon the stopping of the traveling element, and means to position said intermediate member so that the impulses of said second member will move said first member, said last-named means moving into operative position only after a predetermined number of revolutions of said rotating element. 55
28. In combination with a rotating element and a traveling element, stop mechanism, a member moved in one direction by the traveling element, a member actuated by the rotating element, means carried by said second member to move said first member in the opposite direction, and a member to position said last-named means in operative 60 position, said first and second members cooperating to actuate said stop mechanism upon the stopping of the traveling element. 65
29. In combination with a rotating element and a traveling element, means for automatically stopping the rotating element upon the stopping of the traveling element, and manually operable means adapted to disorganize the automatic stopping means at will. 70
30. In a stop mechanism, a rotating member, a traveling member, an oscillating stop member, means cooperating with the stop member and acting when the movement of the traveling member ceases to render operative the stop member, in combination with means co-operating with the stop member to enable said stop mechanism to be manually disorganized at will. 75
31. In combination, record rotating means, sound reproducing means associated therewith, means for stopping the record rotating means automatically at the completion of the record, and other means adapted to render inoperative said stopping means. 80
- In testimony whereof I have signed this specification. 85
- JOHN E. RENHOLDT. 90
